UNITED STATES PATENT OFFICE

2,532,453

CHAIR HAVING A TILTING SEAT AND BACK UNIT

Paul A. James, Louisville, Ky.

Application September 18, 1946, Serial No. 697,785

6 Claims. (Cl. 155—77)

1

The present invention relates to an improved construction of a platform rocker and more specifically pertains to a novel fulcrum or pivoting connection between the platform and the chair seat and back unit together with an improved adjusting means for shifting the position of said fulcrum to suit the convenience of the user.

The principal objects of this invention are to provide a platform rocker having an adjustable fulcrum pivotally connecting the platform and the rocker unit; to provide an improved and efficacious structure for supporting the fulcrum and for permitting longitudinal shifting of the point of fulcrum support; and to provide a construction of the character hereinbefore mentioned which is particularly adapted to maintain the fulcrum in its adjusted position until the same is manually varied by the operator.

These, together with various other auxiliary objects of the invention, which will later become apparent as the following description proceeds, are realized by my invention, one embodiment of which has been illustrated by way of example only in the attached drawings, wherein like numerals indicate similar parts throughout the several views, and wherein:

Figure 1 is a side elevational view of the platform rocker;

Figure 2 is a front elevational view of the device shown in Figure 1;

Figure 3 is a top plan view of Figure 1;

Figure 4 is a rear elevational view of Figure 1;

Figure 5 is a vertical sectional view taken substantially upon the section line 5—5 of Figure 2;

Figure 6 is a vertical sectional view taken substantially upon the section line 6—6 of Figure 1;

Figure 7 is a perspective view illustrating the platform rocker;

Figure 8 is a sectional view showing a detail of construction and is taken substantially upon the section line 8—8 of Figure 6; and,

Figure 9 is a sectional view similar to Figure 8 but taken substantially upon the section line 9—9 of Figure 6, with the cover plate removed.

Attention is now directed more specifically to the accompanying drawings, wherein numeral 10 designates generally the platform, or supporting frame, forming the base of the invention while 12 designates as an entirety the combined, rigid, seat and back unit of the rocker. The supporting frame or platform may conveniently consist of a pair of spaced, parallel, longitudinally extending support members 14 and 16 which are joined and supported in any suitable manner, and which are associated with arm sup-

2

ports 18 and 20 and united therewith in any suitable manner as shown. The frame support members 14 and 16 are provided with transversely aligned and registering apertures 22 and 24 respectively. These apertures are identically formed and as shown in Figure 9, are generally of an inverted heart shape. These apertures each consist of a pair of longitudinally spaced notches 26 and 28, which have a dividing rib 30 therebetween for a purpose to be later set forth.

The combined seat and back unit indicated generally at 12, comprises a generally rectangular seat portion including a pair of parallel, laterally spaced and longitudinally extending support members 34 and 36, which are suitably braced and reinforced as desired and which have rigidly attached thereto a generally rectangular back member 38. The seat unit is so proportioned as to snugly fit within the confines of the platform member, with the lateral support members of the seat disposed between and in parallel relation to the corresponding laterally spaced support members of the frame. As shown in detail in Figure 8, each of the lateral support members of the seat unit is provided with an aperture 40, these apertures being in transverse alignment with each other and being adapted to register with the apertures 22 and 24 in the frame support members 14 and 16. As will be evident, the apertures 40 are identical to those of the frame members, but are arranged in an inverse position, whereby, as shown best in Figures 8 and 9, the sets of longitudinally spaced notches 42 and 44 of the apertures 40 are adapted to cooperate with the corresponding notches 26 and 28 of the apertures 22 and 24, to provide a substantially cylindrical or circular bearing for a purpose to be later set forth. As shown in Figure 8, the notches 42 and 44 have a downwardly extending dividing rib 46 therebetween, whereby the apertures 40 are substantially identical to but inverted in respect to the apertures 22 and 24.

A rod, 48, forming an axle or fulcrum extends through each of the apertures 22 and 24 and 40 and is adapted to selectively seat within the aligned apertures 26 or 28 formed in the frame members 14 and 16 and to support by seating engagement thereon the selective transversely aligned apertures 42 or 44 in the frame members 50 of the seat unit supporting members 34 and 36. Suitable spring members 50 which may be in the form of coil springs, are secured to the forward end of the chair seat unit and the platform, in order to yieldingly urge the chair unit into the customary position for use. A pull chain 52 has

one end anchored to the fulcrum or axle 48 intermediate the ends thereof, and extends through a suitable aperture 53 in the rear of the seat unit and terminates in a ring 54 to facilitate actuation by the user.

As will be readily understood, the downward weight of the seat unit assisted by the tension of the springs 50, causes the selected notches 42 and 44 of the seat unit to engage the upper surface of the fulcrum or rod 48, and by reason of the depending rib 46 tends to maintain the fulcrum in its selected set of notches. When the rod is shifted to the other set of notches it will be seen that the fulcrum of the rocker has been adjusted longitudinally of the support frame members and consequently the seat unit will assume a different inclined position for a given weight of occupant. By reason of the relatively reversely disposed heart-shaped apertures of the seat unit support members and the platform support members, it will be seen that a pair of longitudinally spaced fulcrum journal bearings has been provided which may be selectively engaged by the supporting dowel or pivot axle.

I desire at this point to call attention to the simplified manner of installing and assembling the fulcrum in the seat and platform units. For this purpose, the axle 48 may be laterally inserted from either side of the support members 16, 16, 34 and 36, and when installed in position, may be retained therein as by suitable cover plates 55 secured as desired to the outside of the platform support members 14 and 16 to cover the apertures 22 and 24.

I claim:

1. A rocker comprising a supporting frame, a seat and back unit, pivot means mounting said seat and back unit upon said supporting frame, means for adjusting the position of said pivot means, said frame including spaced lateral supporting members, said seat including spaced lateral members parallel to and received within said frame supporting members, said pivot means including an axle mounted in said frame lateral members and said seat lateral members, each of said lateral members having a set of contiguous axle receiving notches, the sets of notches in said frame lateral members being inversely positioned but registering with the sets of notches in said seat lateral members.

2. A rocker comprising a supporting frame, a seat and back unit, pivot means mounting said seat and back unit upon said supporting frame, means for adjusting the position of said pivot

means, said frame including spaced lateral supporting members, said seat including spaced lateral members parallel to and received within said frame supporting members, said pivot means including an axle mounted in said frame lateral members and said seat lateral members, each of said lateral members having a set of contiguous axle receiving notches, the sets of notches in said frame lateral members being inversely positioned but registering with the sets of notches in said seat lateral members, and spring means connecting said supporting frame and said seat unit and biasing said seat unit into its normal position.

3. A rocker comprising a supporting frame, a seat and back unit, said seat and frame including spaced lateral supporting members, notches including a dividing rib and forming semi-spheres in said seat, notches including a dividing rib and forming semi-spheres in said frame, said notches being in inverted spaced aligned relation to form circular bearings and an axle mounted in said seat and frame bearings for adjustable rocking movement of said seat.

4. A rocker comprising a supporting frame, a seat and back unit, said seat and frame including spaced lateral supporting members, heart shaped notches in said frame, inverted heart shaped notches in said seat, said notches being in spaced aligned position and forming circular bearings, an axle mounted transversely in said seat and frame bearings for adjustable rocking movement of said seat, and cover plates secured on said support members over the notches therein.

5. The combination of claim 4 wherein tension means are secured in said frame and seat for limiting movement of said rocker.

6. The combination of claim 3 wherein tension means are secured in said frame and seat for limiting movement of said rocker.

PAUL A. JAMES.
